CAN OPENING AND SPOUT FORMING
DEVICE

Charles J. Aulbach, Syracuse, N. Y., assignor to
Continental Can Company, Inc., New York,
N. Y., a corporation of New York

Application December 19, 1934, Serial No. 758,300

6 Claims. (Cl. 221—23)

The present invention relates to new and useful improvements in a can opening and spout forming device which may be used to form a pouring opening in the can end and to shape the can body wall adjacent the opening in order to provide a pouring spout through which the contents of the can may be dispensed.

An object of the invention is to provide a can opening and spout forming device which is constructed so that an opening in the can end may be first formed and then the body wall of the can may be shaped to provide a pouring spout.

A further object of the invention is to provide a can opening and spout forming device having a pivoted spout forming member which, when in one position, serves as a handle to which pressure may be applied in forming the opening in the can end and which may be moved about its pivot after the opening has been formed to shape the can body wall to form a pouring spout.

A further object of the invention is to provide a can opening and spout forming device wherein means are provided for forming an opening in the can end and wherein cam means, operable after the opening has been formed, are provided for shaping the body wall of the can to form a pouring spout.

The above and other objects of the invention will in part be obvious and will be hereinafter more fully pointed out.

In the accompanying drawing—

Figure 1 is a plan view of the can opening and spout forming device in position on the end of a can;

Fig. 2 is a side elevation of the device after the opening has been formed in the can end;

Fig. 3 is a side elevation of the device after the spout has been formed in the can body;

Fig. 4 is a developed fragmentary plan view of the end of the base member on which the cutter is formed;

Fig. 5 is a front elevation of the base member showing the cutter, and

Fig. 6 is a fragmentary plan view of the can end after the opening and spout have been formed.

The invention relates generally to a can opening and spout forming device which includes a base member having a depending cutter formed integral therewith. The base member is adapted to be positioned on the top of the can and is provided with means for engaging the double seam to prevent endwise movement thereof relative to the can end. The cutter has a piercing point and diverging cutting edges which merge into parallel cutting edges extending at right an-

gles thereto. The base member carries a spout forming device which includes a lever pivotally mounted between the parallel cutting edges. When the lever extends away from the base member in substantially the plane thereof, the end thereof abuts against the base member so that pressure can be applied to the lever to aid in forcing the cutter downwardly for cutting the opening in the can end. The lever is provided with a cam face which remains in an inoperative position until the lever is pulled upwardly after the cutter has been forced down and the opening has been formed in the can end. When the lever is pulled up, the cam face engages the body wall of the can adjacent the opening and forces the same outwardly to form a pouring spout.

Referring more in detail to the accompanying drawing, the can comprises a can body 10 to which the can end 11 is secured by a double seam 12. This is the usual type of hermetically sealed can in which products are marketed. The can may be used for liquid products, and the invention has to do particularly with a can opening and spout forming device for opening a sealed can and preparing the same for dispensing liquid contents. Lubricating oils are being marketed in hermetically sealed cans, and the can opening and spout forming device of the present invention may be used quickly and efficiently at a filling station or garage for opening and preparing the can for the dispensing of the lubricant contained therein to a motor. The device of the present invention is further advantageous in that the body wall of the can is deformed in the preparation of the pouring spout so that the can cannot be fraudulently used again to market an inferior product.

The can opening device includes a base or supporting member 13 which is formed of suitable metal. The central portion 14 of the base member 13 is offset slightly downwardly with respect to the plane thereof, in order to leave side portions 15. The offset portion 14 is provided with a depending lug 16 which is cut and bent downwardly. The free edge of the lug is curved to conform to the curvature of the inner edge of the double seam 12, so that when the device is placed over the end of a can, the lug 16 will rest against the inner edge of the double seam to prevent endwise movement of the base member 13 with respect to the can end. The base member 13 is provided with two downwardly bent lugs 17 at the end thereof. The lugs 17 are adapted to bear against the inner edge of the double seam of a larger can, in which case, the lug 16 serves no

function. For purposes of illustration, the can opening and spout forming device is shown in connection with a relatively small can, such as a one quart size.

- 5 The base member 13 is provided with a cutter device which is integral therewith. There is shown, in Fig. 4, a developed plan view of the end of the base member on which the cutter is formed. The member 13 is slit along the lines 10 $a-b$, $b-c$, $a'-b'$, $b'-c'$. A centrally disposed longitudinal slot 18 is formed in the end of the member and circular apertures 19, 19a are formed on opposite sides of the slot. There are also provided openings 20, 20a on opposite sides 15 of the slot and these openings communicate with the slits $b-c$, $b'-c'$. The triangular portions 21, 21a of the member, wherein the apertures 19, 19a are located, are bent along lines $b-d$, $b'-d'$, respectively, to lie parallel to one another with the apertures 19, 19a in alignment. The pointed end 20 of the member 13 is bent downwardly along the line $e-f$, so that the slit edges of the portions 21, 21a abut against the portion between the slits $b-c$, $b'-c'$. A pin 25, having a lever 26 25 mounted thereon within the slot 18 in the cutter, is supported in the openings 19, 19a, between the parallel cutting edges 21, 21a. The side portions 22, 22a adjacent the slits $b-c$, $b'-c'$, are bent downwardly to a position wherein they lie opposite the openings 19, 19a, respectively, and thus prevent the pin 25 from becoming disengaged. The lever 26 is provided with an abutment portion 27 which bears against the under side of the base member 13 behind the end of the 30 slot 18 when the handle extends away from the base in substantially the plane thereof, as shown in Figures 1 and 2. The lever 26 is provided with a cam edge 28 which is inoperative when the lever is in the position shown in Fig. 2.
- 40 In order to form an opening in a can end and to form a pouring spout, the base member 13 is placed over the end of the can with the depending lug 16 resting against the inner edge of the double seam 12. The piercing point 23 of the cutter will enter the can end 11 at the point y , in Fig. 6, just within the double seam. The cutter is provided with cutting edges 24, 24a which diverge from the piercing point 23 and merge into the parallel cutting edges 21, 21a. The lever 26 45 mounted on the pin 25 within the slot 18 in the cutter is turned to the position shown in Fig. 2, with the abutment portion 27 bearing against the under side of the base member 13. The operator, then placing one hand on the portion 14 of the 50 base member and placing the other hand on the lever 26, may press down and cause the piercing point 23 to enter the can end 11 at the point y (Fig. 6). Further descent of the cutter will cause the cutting edges 24, 24a to cut the can end along lines $y-g$ and $y-h$ (Fig. 6). Further downward movement of the cutter will cause the parallel cutting edges 21, 21a to cut the can end along lines $h-k$ and $g-l$, respectively, and at the same time, curl back the metal 11a in order to form 55 the opening in the can end. In this position of the cutter, as shown in Fig. 2, the cam face 28 on the lever 26 is inoperative and is dropped below the edge of the double seam 12 adjacent the formed opening. The edge portions 22, 22a rest 60 on the double seam, as shown in Fig. 2, and thus serve as a stop to prevent further movement of the device. The operator, in order to form the pouring spout still presses upon the base member with one hand and raises the lever 26 with the 65 other to the position shown in Fig. 3. The cam 70
- 75

face 28 will force the body wall of the can outwardly to form a pouring spout 29, after the formation of which the device may be removed and the can tilted to dispense the contents thereof. It is to be noted that the ends of the portions 22, 22a extend at an angle so that the outer edges extend farther than the inner edges so that the formation of the spout 29 will not prevent the portions 22, 22a to continue to serve as a stop. 5

From the foregoing description it will be apparent that a highly efficient can opening and spout forming device is herewith provided wherein a pivoted spout forming device serves as a handle for operating the can opening device and remains inoperative until the opening is 15 formed, at which time it may be swung about its pivot to form a pouring spout adjacent the formed opening. 10

It is to be clearly understood that minor changes in the details of construction and arrangement of parts may be made without departing from the scope of the invention as set forth in the appended claims. 20

Having thus described the invention, what I claim as new and desire to secure by Letters- 25 Patent, is—

1. A can opening and spout forming device comprising a base member having a cutter depending therefrom for forming an opening in the can end, and a spout forming member pivotally mounted on said cutter, said spout forming member serving as a handle for said cutter in forming the opening in the can end and adapted to be turned about its pivot after the formation of said opening to shape the body wall of the 30 can to form a pouring spout. 35

2. A can opening and spout forming device comprising a base member having means for engaging the double seam on the can end, a cutter depending from said base member and formed 40 integral therewith, a lever pivotally mounted on said base member and adapted to be positioned so as to form an extension of said base member and to serve as a handle for applying pressure to cause the cutter to penetrate the 45 can end, and cam means on said lever operable upon the upward movement thereof to shape the body wall of the can into a pouring spout after the opening in the can end has been formed.

3. A can opening and spout forming device 50 comprising a base member, a cutter depending from said base member and including parallel cutting members, means on said base member for positioning the same on the can end, a spout forming device including a lever having a cam 55 end, and means for pivotally mounting said lever between said parallel cutting members, said lever adapted to serve as a handle to which pressure may be applied for forming an opening in the can end when in one position and adapted 60 to be swung about its pivot after the opening in the can end has been formed to bring said cam end into operation to form a pouring spout in the body wall of the can.

4. A can opening and spout forming device 65 comprising a base member, a cutter integral with said base member and depending therefrom and including a piercing point and parallel cutting members, means on said base member for positioning the same on the can end to prevent 70 endwise movement relative thereto, a lever pivotally mounted between said parallel cutting members, said lever having an abutting surface adapted to bear against the under side of said base member when said lever is disposed in sub- 75

stantially the plane thereof whereby to afford a handle for forcing said cutter into the can end, and a cam surface on said lever adjacent its pivot point for forming a pouring spout in the body wall of the can by turning the lever about its pivot out of the plane of said base member after the opening has been formed in the can end.

5. A can opening and spout forming device comprising a base member, a cutter including parallel cutting members depending from said base member and adapted to form an opening in the can end, means on said base member for engaging the double seam to prevent endwise movement thereof relative to the can end, said parallel cutting members having registering openings therethrough, a pin mounted in said openings, a lever pivotally mounted on said pin, said lever adapted to be positioned so as to form 15 an extension of said base member whereby to serve as a handle for applying pressure to cause said cutter to penetrate the can end, and cam means on said lever adjacent the pivot pin operable by swinging the lever after the can opening

has been formed to shape the body wall of the can into a pouring spout.

6. A can opening and spout forming device comprising a base member having an integral cutter depending therefrom, said cutter including a slotted front portion having a piercing point and parallel cutting members, having registering openings therethrough, a pin mounted in said openings, depending portions on said base member for retaining said pin in position, 10 means on said base member for positioning the same on the can end, a lever pivotally mounted on said pin and extending through said slot, said lever having an abutting surface adapted to bear against the under side of said base member when 15 positioned to serve as a handle for applying pressure to cause the cutter to penetrate the can end, and cam means on said lever adjacent the pivot pin operable upon the turning of said lever after the can opening has been formed to 20 shape the body wall of the can to form a pouring spout.

CHARLES J. AULBACH.
